UNITED STATES PATENT OFFICE.

WILLIAM R. CARROLL, OF MANY, LOUISIANA.

DERAILMENT BRAKE APPLIANCE.

1,089,623.

Specification of Letters Patent. Patented Mar. 10, 1914.

Application filed November 1, 1913. Serial No. 798,711.

To all whom it may concern:

Be it known that I, WILLIAM R. CARROLL, a citizen of the United States, residing at Many, in the parish of Sabine and State of Louisiana, have invented a new and useful Derailment Brake Appliance, of which the following is a specification.

The present invention appertains to a derailment brake appliance, and is particularly an improvement over the derailment brake disclosed in my former Patent #732,921, issued July 7, 1903.

It is the primary object of the present invention to provide an appliance of the nature indicated, which shall be so constructed and operable as to open the train pipe, should the truck wheels of a car become derailed, the present device being comparatively simple, unencumbering and inexpensive in construction, as well as being simple practical and efficient in its use.

It is also the object of the present invention to provide a device of the character specified, which will under ordinary conditions permit of the swaying and vertical movements of the car body without the liability of opening or bleeding the train pipe, the device being of unique construction and operation in order that the train pipe may be unfailingly opened, should the truck wheels become derailed.

With the foregoing general objects outlined, and with other objects in view, which will be apparent as the nature of the invention is better understood the present invention resides in the combination and arrangement of parts and in the details of construction hereinafter described and claimed, it being understood that changes in the precise embodiment of the invention herein disclosed, can be made within the scope of what is claimed, without departing from the spirit of the invention.

The invention has been illustrated in its preferred embodiment in the accompanying drawings, wherein:—

Figure 1 is a fragmental side elevation of a railway car having the present appliance applied thereto. Fig. 2 is a cross sectional detail of the car, illustrating the present appliance. Fig. 3 is an enlarged sectional view of one of the air chambers or compartments and associate parts. Fig. 4 is a bottom view of the air chamber or compartment. Fig. 5 is a fragmental plan view of one of the air chambers with its hanger and hanger arm.

In the drawings, the numeral 1 designates the car body, which has mounted below the bottom thereof, the train pipe 2, said body being carried by the truck 3 including the 60 rail engaging wheels 4.

In carrying out the present invention, a hanger or pendant 5 is suspended over each rail, from a carrier or bearing 6 secured to the bottom of the car body, the hanger 5 being loosely connected to the carrier or bearing 6. It is preferable to employ a pair of hangers 5 with each truck of each car, the hangers of each pair being oppositely disposed adjoining certain wheels of the truck, 70 as illustrated in the drawings. The hangers or pendants 5 are preferably fashioned from bars or straps of metal, the upper end portions of which are formed into springs, as at 7, and the lower or free ends of which 75 carry the air chambers or compartments, indicated generally at 8. The hangers 5 are adapted to flex laterally and are connected intermediate their ends by a tie rod or stay 9, in order that the hangers will vibrate or 80 oscillate laterally in unison.

A guide 10 is provided for each hanger or pendant 5, the said guide being preferably fashioned from a rod or bar of metal, bent intermediate its ends, and having a guiding 85 loop or eye 11 at its intermediate point, through which the hanger 5 passes. The terminals of each guide 10 are connected or attached to bearings or carriers 12 secured to the bottom of the car body, and the portions of the guide arms or sections adjoining the terminals being flattened, as at 13, to act as leaf springs. The spring portions 13 will permit the guides to flex laterally with the hangers, as will be apparent, and 95 will normally maintain the hangers in position over the rails.

A horizontal arm 14 is attached to each hanger or pendant 5, and projects behind the inner side or face of the respective wheel 100 4, the free ends of the arms 14 standing between the opposite wheels, and being preferably provided with rollers or wheels 15 to contact with the inner or adjoining faces of the wheels. The rollers 15 are preferably 105 normally spaced from the wheels, to permit the slight play between the wheels and hangers under ordinary conditions.

Returning specifically to the air chambers or compartments 8 each of the same embodies a hollow body or casing 16, which is elongated and disposed horizontally and

transversely over the respective rail. The intermediate portion of the body or casing 16 is arched upwardly as at 17, and the end portions 18 of the body or casing are provided with lower openings, as best seen at 18^a in Fig. 3. Closure plates 19 are clamped on the bottoms of the end portions 18 of the body or casing 16, bolts 20 being connected to the plates 19 and engaging the upper portion of the body 16 to tightly secure the plates 19 in position. The casing 16 and the plates 19 are preferably provided with ground joints in order to prevent leakage. Each of the plates 19 is provided with a central opening or outlet port 21, which has a seat 22 at its inner end, against which a valve 23 is seatable, the valve having a longitudinally grooved stem 24 slideable through the opening 21 and normally depending below the plate 19. The plate 19 is also provided in its bottom face, with grooves 25 extending radially from the opening 21 for the purposes which will hereinafter appear. Each of the air chambers or compartments 25 is connected to the train pipe 2, and to this end, each of the bodies or casings 16 is provided with an upstanding nipple 26 at one end portion 18, a hose or flexible tubing 27 having one end engaged over the nipple 26, and having its other end attached to the train pipe 2 to communicate therewith.

In connecting each of the casings or bodies 16 to the respective hanger or pendant 5, the lower end of the hanger or pendant is provided with a vertically elongated opening or slot 28, and a pin 29 is engaged through the slot 28 and terminally engages the back of the body 16 to pivotally and slidably connect the body to the hanger. Each of the hangers 5 is also equipped with a pair of leaf springs 30 adjoining its lower end, the free ends of which project toward but are normally spaced slightly from the backs of the end portions 18 of the body 16.

The air brakes are held in inoperative position by the air which is under compression within the train pipe, hose sections 27 and air chambers 8. The valves 23 being seated by the compressed air will prevent the air from escaping under normal conditions. The arched portions 17 of the casings or bodies 16 being disposed directly over the rails will permit the car body to sway and vibrate without the liability of the valves 23 being opened, it being noted that the said valves are disposed at the opposite sides of the rails. The hose sections 27 will also permit the hangers or pendants 25 to swing slightly without interference, while the pivotal connections of the casings 16 with the hangers will permit the casings to swing laterally to a limited extent, as may be desirable.

The entire apparatus is compactly housed and protected underneath the car body, and is also readily accessible from the sides of

the car body, although the apparatus does not encumber the side portions of the car body.

Perchance, should the truck wheels, become derailed, the car body being moved laterally or transversely of the track, and being depressed due to the derailment of the wheels, will move the casings or bodies 16 similarly, and consequently the valves 23 at the respective ends of the casings, will be lifted or raised from their seats by the engagement of the valve stems with the heads or balls of the rails. This will result in opening the train pipe, the air passing out through the openings or ports 21, which will bring the automatic air brakes into operation to check or arrest the movement of the train so as to avoid serious results, such as a wreck, or the like.

Attention is directed to the fact that although the valves, which are of the check valve type are disposed at the opposite sides of the rails under normal conditions, certain of the valves will be brought into engagement with the rails when the wheels become derailed toward one side or the other, whereby the opening or bleeding of the train pipe will be effected in an unfailing manner. The grooves 25 in the bottoms of the plates 19 extending radially from the openings 21, will permit of the escape of air, should the openings 21 be closed due to the respective plates 19 seating upon the rail heads or balls.

The tie or stay bar 9 will cause both of the hangers to move simultaneously, that is, transversely of the car body, which is of particular advantage in connection with the arms 14. Thus, should the wheels become derailed without the car body moving laterally appreciably, the lateral or transverse movement of the wheels will cause one or the other of the wheels to engage one of the arms 14, and consequently, the hangers or pendants 5 will be swung transversely in order that the respective valves 23 may be opened. In this manner, the arms 14 standing between the wheels of one pair, will assure of the lateral movement of the casings or bodies 16 even though the car body is not moved laterally upon the derailment of the wheels. The rollers 15 being normally spaced from the wheels will permit of the proper play of the wheels and car body with respect to one another, as when rounding curves and the like, without appreciably affecting the positions of the casings or bodies 16. The spring portions 7 of the hangers or pendants will permit the lower portions of the hangers to yield vertically, due to the engagement of the casings or bodies 16 with the rails.

It will be observed that the casings or bodies 16 may ordinarily swing slightly transversely of the rails, the casings 16 be-

ing adapted to slide upwardly slightly due to the engagement of the pins 29 carried by the casings through the slots 28 of the hangers. This is of importance inasmuch as 5 when the end portions of the casings 16 engage the rails, the said end portions will be forced upwardly slightly under certain conditions, which will cause the said portions of the casings to engage the respective balancing springs 30 to yieldingly hold the said end portions of the casings against the rails.

From the foregoing, the missions of the various parts of the present appliance will be apparent to those skilled in the art, and 15 the other advantages of the present device will also be obvious without further comment, it being noted that the objects aimed at have been carried out satisfactorily, and that the present device is a desirable one for 20 the purposes intended.

Having thus described the invention, what is claimed as new is:—

1. In a device of the character described, an elongated body adapted to be disposed 25 transversely above a rail, the body being arched intermediate its ends, means for suspending the body from a car body, and air brake controlling means carried by the end portions of the aforesaid body and coöper- 30 able with the rail.

2. In a device of the character described, an air chamber adapted to be disposed transversely of a rail, means for suspending the air chamber from a car body, means for 35 connecting the air chamber to a train pipe, and valves carried by the air chamber at the sides of the rail and arranged to be opened by the rail.

3. In a device of the character described, 40 a car carried hanger, an elongated air chamber adapted for connection with a train pipe and adapted to be disposed transversely of a rail, the said chamber being arched intermediate its ends, the intermedi- 45 ate portion of the air chamber being pivot- ed to the hanger, valves carried by the end portions of the air chamber and coöper- able with the rail, and balancing springs dis- posed between the hanger and the end por- 50 tions of the air chamber.

4. In a device of the character described, a car carried hanger, an air chamber ar- ranged to be disposed transversely over a rail and adapted for connection to the train 55 pipe, the air chamber being pivoted to the hanger to swing transversely, valves for the end portions of the air chamber, and bal- ancing springs between the end portions of the air chamber and hanger.

60 5. In a device of the character described, an air chamber arranged for connection

with a train pipe and adapted to stand trans- versely over a rail, means for suspending the air chamber from a car body, the air chamber having lower outlet at the sides of 65 the rail, and valves seatable over the said ports and having stems depending through the ports for coöperation with the rail.

6. In a device of the character described, a car carried hanger, an elongated air cham- 70 ber adapted to be disposed transversely over a rail and arranged for connection with a train pipe, the air chamber being arched intermediate its ends and being pivoted to the hanger to swing transversely of the 75 rail, the air chamber having lower outlet ports adjoining its ends, valves seatable over the said ports and having depending stems coöperable with the rail, and yield- able balancing means between the end por- 80 tions of the air chamber and the hanger.

7. In a device of the character described, a car carried hanger, a body carried thereby, air brake controlling means carried by the body coöperable with a rail, and means 85 carried by the hanger and coöperable with a car wheel to move the said body trans- versely with the car wheel.

8. In a device of the character described, 90 opposite car-carried hangers, means con- necting them, members carried by the hangers arranged to be suspended over the rails, air brake controlling means carried by the said members and coöperable with the 95 rails, and arms carried by the hangers and coöperable with certain car wheels.

9. In a device of the character described, car-carried hangers, members carried by the hangers and adapted to be disposed trans- 100 versely over the rails, a tie bar connecting the hangers, arms carried by the hangers and coöperating with certain car wheels, and air brake controlling means carried by the aforesaid members at the sides of and coöperable with the respective rails. 105

10. In a device of the character described, a car carried hanger, an elongated body adapted to be disposed above a rail and pivoted intermediate its end to the hanger to swing transversely, air brake controlling 110 means carried by the end portions of the said body and coöperable with the rail, and balancing springs disposed within the hanger and the end portions of the said body. 115

In testimony that I claim the foregoing as my own, I have hereto affixed my signature in the presence of two witnesses.

WILLIAM R. CARROLL.
